INTEREST CALCULATOR

Quentin M. Kline, Dearborn, Mich.

Application August 14, 1943, Serial No. 498,607

7 Claims. (Cl. 235—85)

The present invention relates to an interest or similar calculating or computing device and is designed primarily as an aid in making interest calculations at a predetermined rate for adjusted variable amounts of principal sums and for a plurality of preselected time intervals.

Among the objects of the present invention are:

1. To provide an interest calculating device of simplified design, construction and operation, and in which by a series of positive, simple and readily performed operations, the desired data required for a particular interest calculation is made readily available in a series of vertical columns.
2. To provide an interest or similar type of calculating device which by a simple and readily performed adjusting operation will provide computed data for a plurality of predetermined time intervals and for adjusted amounts of principal units, the device being readily adapted to utilize exchangeable members for presenting various desired types of such data.
3. To provide an interest computing device which by a single series of simple and readily performed adjusting operations will provide the data required for interest computations at a preselected rate for a plurality of predetermined time intervals and for various adjusted amounts of principal sums, the device being such as to be readily adapted to provide data for interest computations at various preselected interest rates.

4. To provide a computing device in a convenient form which is readily usable in making interest computations for various principal sums, and for a plurality of preselected time intervals, the device being characterized by the positiveness of its operation and the various arrangement of the parts which are designed to so display the desired data that errors in the use of the device or in the computation of interest from the data thereon contained are very largely avoided.

Other objects of this invention will appear in the following description and appended claims, reference being had to the accompanying drawing forming a part of this specification wherein like reference characters designate corresponding parts in the several views.

In the drawing:

Fig. 1 is a plan view of the device embodying the present invention with the adjusted member showing an interest computation for a principal sum of \$4,121.00 at an interest rate of 2½%.

Fig. 2 is a cross-sectional view taken substantially on the line 2—2 in the direction of the arrows in Fig. 1.

Figs. 3, 4, 5 and 6 are plan views of the four slide members representing respectively thousands, hundreds, tens and dollars of the principal sum shown as they appear when removed from the body portion of the device embodying the present invention.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation.

Referring to the drawing and particularly to Fig. 1, 10 designates a face portion which is provided with a plurality of apertures 11, which are arranged in the face portion 10 in a plurality of vertical columns, each one of which represent a selected time interval. In the present instance, six such columns are shown, representing respectively one, two, three, four, five and six month time intervals. A plurality of other apertures 11—A are located at the right of the face portion 10, and are arranged in a vertical column so as to indicate the amounts of the principal sum for which the calculation is being made, and here, reading from the bottom to the top, the column is marked to represent dollars, tens, hundreds and thousands.

As shown in Fig. 2, the face portion 10 is secured to a back portion 12 by a plurality of fastening members, such for example as the eyelet devices 17. The back portion 12 and the face portion 10 are spaced from each other by a plurality of longitudinally extending spacer members 13, which act as partitions to divide the space between the face portion 10 and the back 12 into a plurality of longitudinally extending channels 14, in the present instance four in number, one channel being provided for each of the four slide members. Each channel 14 communicates with one aperture 11—A and a series of the apertures 11 which lie in what is in effect a column extending longitudinally across the face portion 10 and substantially at right angles to the said vertical column.

The apertures 11 are preferably spaced in the adjacent vertical column in ascending staggered relation to each other across the width of each longitudinal channel. Where six vertical columns are used as here shown, the preferred arrangement comprises two series of three each of the apertures 11, extending across each longi-

tudinal channel 14. One aperture 11-A is located in each longitudinal channel, and is aligned longitudinally with the bottom apertures 11 in each of the series of such apertures which extend across the width of each longitudinal channel.

A plurality of removable slide members 15 are provided, one each for each longitudinal channel. In the present instance four such slide members are provided for the four longitudinal channels here shown. Each of the four longitudinal channels is labeled on the face 10 so as to indicate the principal sum which is the basis for the selection of the data placed on the movable slide member 15 to be carried in said channel. In the present instance these longitudinal channels represent respectively thousands, hundreds, tens and dollars of the principal sums for which interest computations are to be made. The four slide members 15 are correspondingly labeled thousands, hundreds, tens and dollars so that the proper slide is in all instances readily selected for insertion in the proper channel.

Each slide 15 as shown in Figs. 3, 4, 5 and 6, exhibits the interest calculating data on the face portions thereof in three longitudinally extending columns, and in ten inclined staggered vertical columns corresponding to ten longitudinally adjusted positions in which each slide member may be used so as to bring into registry with the apertures 11-A the ten digits 16 which are placed thereon to represent the ten units of the particular portion of the principal sum. Each slide, therefore, represents principal amounts of from zero to nine, one slide is calibrated in terms of dollars, another in terms of tens, another in terms of hundreds and another in terms of thousands. Thus the slide member 15 will be seen to contain the desired data in such a manner that when the correct number of units of the principal sum is brought in registry with the apertures 11-A, the data which is brought in registration with the apertures 11 and is displayed therein will correspond to the amount of interest calculated at the rate of 2½% for the various time intervals represented by the vertical columns in which the apertures 11 are arranged. The staggered arrangement of the longitudinally adjacent apertures 11 separates the vertical columns in such a manner as to avoid the possibility of errors which might occur if the data for each time interval was aligned longitudinally with the data in the vertical column adjoining the adjacent time interval column. The arrangement is such that by a single adjustment of each of the slide members 15, all of the required data to make the interest calculation for various preselected time intervals, is displayed at one time through the apertures 11 provided in the face plate 10.

The data on each member 15 represents calculated interest amounts at a preselected rate and these figures when arranged as shown in Figs. 3, 4, 5 and 6 are readily brought into positive alignment with the apertures 11 in the face portion 10 to provide the data from which the interest calculation is made. By the substitution of other slide members for the separate and readily removable slide members 15, it is possible to provide other data which may be displayed through the apertures 11 in a similar manner so as to permit the making of various types of calculation by the simple expedient of providing sets of slide members 15 on which the desired data is provided. Thus while there is here shown by way of example an interest computer

for computing interest at the rate of 2½%, it will be seen that other slide members may be provided having the interest calculating data required for making computation at other rates.

5 By substitution of such other members for the member 15 here shown, it will be seen that interest may be calculated at any desired rate by the device of the present invention. For example, if a universal interest calculator is desired, slides similar to the slides 15 may be provided containing data computed for various interest rates for the time intervals shown on the face portion of the calculator and for the particular amounts represented by each slide member. Thus simply by substituting one set of slide members for another set of slide members, interest calculations at various rates may be made readily.

20 The device of the present invention may be readily used in making interest calculations, for example in building and loan or savings account records. Likewise, the device may be used in figuring interest due on land contracts, mortgages, and the like. When used, the slide members 15 are moved longitudinally of the face member 10 so as to bring into registry in the vertical column of apertures 11-A the amount of the principal sum. In Fig. 1 the device is shown adjusted to provide interest calculations 25 at the rate of 2½% for a principal sum of \$4,121.00. In this instance the slide 15 in the longitudinal column representing thousands has been moved to the right so as to bring the numeral four into registry in the aperture 11-A, the slide 15 in the longitudinal column representing hundreds has been moved to the right to bring the numeral one into registry with the aperture 11-A therein, the slide 15 in the longitudinal column representing tens has been moved to the right to bring into position in the aperture 11-A the numeral two and the slide 15 in the longitudinal column representing dollars has been moved to the right to bring into registry in the aperture 11-A the numeral one. Thus by looking downwardly on the vertical column of apertures 11-A it will be seen instantly that the principal sum for which the interest calculation is to be made is \$4,121.00. By noting the data on the end portion of each of the slide members 15, it will be seen that the interest is to be computed at the rate of 2½%. The six vertical columns on the face portion of the calculator represent respectively the periods one month, two months, three months, four months, five months and six months, and by totaling any one of the vertical columns, the total interest computation for such time period is readily made. For example interest on \$4,121.00 at 2½% for one month would be computed by adding the figures \$8.35, \$.21 and \$.04, which appear in the vertically arranged apertures 11 under the column headed one month.

30 35 40 45 50 55 60 65 70 75 If the interest period is greater than the time period shown in any one of the vertical columns, it may be necessary to total the interest in more than one column and to add such amounts in order to complete the interest calculation. Thus for example, if the time interval for which interest is to be calculated is nine months, the interest data showing in the vertical column headed six months is totaled, together with the interest data appearing under the column three months.

While the present calculator is here shown by way of example for the computation of interest in a plurality of selected monthly periods, it is

to be understood that the device may be readily adapted for the computation of interest for other time periods by the simple expedient of changing the time indicating data on the face portion of the device and by providing slide members 15 on which the desired data is suitably arranged.

While a very important field for use of the present device is that of interest calculations, it is to be understood that the device may be used for various types of calculations or mathematical computations. By changes in the location and arrangement of the apertures of 11 and 11—A and by corresponding changes in the arrangement of the data carried on the removable slide members 15, the device is readily adaptable for use in many other fields.

From the foregoing it will be seen that the computing device of the present invention possesses a simplified design providing a simplified and positive operation which permits the ready calculation and computation of tabulated information by a single adjustment of each of the slide members 15 so as to vary the principal amount of the calculation. The desired data is displayed in a plurality of vertical columns from which the displayed information may be readily taken by the user of the device. The device is positive in its operation and the data appearing thereon is so arranged that errors in transcribing the data and in the use thereof for the making of computations are very largely avoided.

Having thus described my invention, I claim:

1. A device for computing interest at a given rate on variable sums for a plurality of different predetermined time intervals, and comprising a body portion divided into a plurality of longitudinally extending separated channels, a face portion enclosing one face of each of said channels, and having a series of fixed apertures therein communicating with said channels and arranged in a plurality of vertical columns, each of which is marked to correspond to a single time interval for which interest is to be computed, and having other apertures arranged in a separate vertical column to indicate the principal sum upon which interest is to be computed, a removable slide in each of said channels, each of said slides carrying interest calculations computed at a given rate and figures denominating various principal sums on the face thereof, and adapted for movement longitudinally of one of said channels to bring selectively into alignment simultaneously with all of said apertures communicating with said channel, an interest calculation corresponding to each of the predetermined time intervals indicated thereon for the adjusted principal sum shown in the aperture arranged to indicate said sum.

2. A computing device as claimed in claim 1 and further characterized in that six vertical columns of apertures are provided to represent respectively six time intervals and in that the longitudinally adjacent apertures in said column are arranged in vertically and horizontally staggered relation to each other.

3. A computing device as claimed in claim 1 and further characterized in that the body portion comprises a face portion and a back portion secured in spaced relation to each other, and in that a plurality of longitudinally extending spacer members are provided to act as partitions for dividing said space into a plurality of separate longitudinal channels.

4. A computing device as claimed in claim 1 and further characterized in that the data required for the computation is arranged in a plurality of separate columns extending longitudinally of each slide member and spaced to display said data in the said apertures arranged in said vertical columns.

5. A computing device as claimed in claim 1 and further characterized in that a plurality of vertical columns of apertures are provided to represent respectively a plurality of time intervals, and in that the longitudinally adjacent apertures are arranged in horizontally spaced and vertically staggered relation to each other across the width of each longitudinal channel provided in the space between the face portion and the spaced back portion of the device, and in that a plurality of spacer members are provided between said face portion and said back portion and act as partitions to separate the said space into a plurality of separate longitudinal channels.

6. A computing device as claimed in claim 1 and further characterized in that six vertical columns of apertures are provided to represent respectively six time intervals, and that the longitudinally adjacent apertures are arranged in staggered relation to each other, and in that the data provided on each slide member is arranged in a plurality of separate columns extending longitudinally of the member in staggered columns so spaced with relation to said apertures that preselected data will be displayed through said apertures upon adjustment of said slide members therein.

7. A computing device as claimed in claim 1 and further characterized in that six vertical columns of apertures are provided to represent respectively six time intervals and in that the longitudinally adjacent apertures in said column are arranged in staggered relation to each other, and in that the body portion comprises a face portion and a back portion secured in spaced relation to each other by a plurality of longitudinally extending spacer members which act as partitions to divide said space into a plurality of separate longitudinal channels, and in which the data is arranged in a plurality of separate columns extending longitudinally of each slide member and in staggered vertical columns spaced with relation to said staggered apertures to display the desired data in said aperture upon longitudinal adjustment of said slide member.

QUENTIN M. KLINE.
